UNITED STATES PATENT OFFICE.

ABBOT A. LOW, OF HORSESHOE, NEW YORK.

DESIGN FOR A CABINET.

No. 39,593.

Specification for Design.

Patented Sept. 29, 1908.

Application filed April 29, 1908. Serial No. 430,030. Term of patent 14 years.

To all whom it may concern:

Be it known that ABBOT A. Low, a citizen of the United States, and resident of Horseshoe, in the county of St. Lawrence and State of New York, has invented a new, original, and ornamental Design for a Cabinet, of which the following is a specification, reference being had to the accompanying drawing, forming part thereof.

Figure 1 is a front elevation of a cabinet, showing my new design. Fig. 2 is a plan view of the same.

The cabinet comprises a vertical body portion provided at either side with uprights or posts and at its lower edge with a rectangular base. Upon the front of the body portion a number of receptacles are provided for holding implements, pens, pencils, etc.

One of the uprights or posts is provided at its upper end with an ornamental receptacle or vase and at the upper end of the other post is provided a vertical support upon which the lamp holder is mounted.

I claim:

The ornamental design for a cabinet as shown and described.

ABBOT A. LOW.
